US0D1095467S

(12) **United States Design Patent** (10) **Patent No.:** **US D1,095,467 S**
(45) **Date of Patent:** **** Sep. 30, 2025**

(54) **PROTECTIVE OUTLET COVER**

(71) Applicant: **Hubbell Incorporated**, Shelton, CT (US)

(72) Inventors: **Krzysztof Korcz**, Granger, IN (US); **Steven Johnson**, Buchanan, MI (US)

(73) Assignee: **Hubbell Incorporated**, Shelton, CT (US)

(**) Term: **15 Years**

(21) Appl. No.: **29/878,283**

(22) Filed: **Jun. 20, 2023**

Related U.S. Application Data

(62) Division of application No. 29/739,781, filed on Jun. 29, 2020, now Pat. No. Des. 993,929.

(57) **CLAIM**

The ornamental design for a protective outlet cover, as shown and described.

DESCRIPTION

FIG. 1 is a front perspective view of the design; FIG. 2 is a rear perspective view of FIG. 1;

FIG. 3 is a front view of FIG. 1;

FIG. 4 is a rear view of FIG. 1;

FIG. 5 is a right-side view of FIG. 1;

FIG. 6 is a left-side view of FIG. 1;

FIG. 7 is a top view of FIG. 1; and,

FIG. 8 is a bottom view of FIG. 1.

The broken lines shown on the drawings depict portions of the protective outlet cover that form no part of the claimed design.

1 Claim, 40 Drawing Sheets
